UNITED STATES PATENT OFFICE.

ALFRED BODE AND KARL BÖTTCHER, OF BENRATH, GERMANY.

FLOATING CRANE AND THE LIKE.

No. 840,684.

Specification of Letters Patent.

Patented Jan. 8, 1907.

Application filed August 21, 1905. Serial No. 275,060.

To all whom it may concern:

Be it known that we, ALFRED BODE and KARL BÖTTCHER, subjects of the King of Prussia, German Emperor, and residents of 5 Benrath, near Düsseldorf, in the Province of the Rhine, German Empire, have jointly invented certain new and useful Improvements in Floating Cranes and the Like, of which the following is an exact specification.

10 Our invention relates to floating cranes and the like capable of being rotated and particularly adapted for hoisting heavy loads.

It is well known that floating cranes for small loads are constructed by arranging a 15 disk-turning crane on a pontoon. In practice it is impossible to enlarge such a turning disk construction for carrying heavy loads—for example, of one hundred tons and upward—and hitherto larger floating cranes 20 have been made in the form of shears or of similar construction. A rotating floating crane for heavy loads has not yet been built.

The object of the present invention is to 25 produce a crane for heavy loads which can be easily built. According to one construction, the whole free pontoon surface can be reached by the crane-hook, and the pontoon can be made as small as possible by mounting a stationary or movable counterweight somewhat 30 over the edge of the pontoon.

In the mode already known for stationary cranes the jib is arranged on a turning support formed like a bell which surrounds the stationary support like a mantle.

35 The present invention consists in arranging a stationary or movable counterbalance on the lower end or lax of the rotatory support surrounding the stationary support like a mantle. By this means the counterbalance 40 is always opposite to the jib when the latter is turned upon the vertical middle axle through the desired angle, whereby the highest stability of the floating crane is obtained. Furthermore, the center of gravity of the 45 whole crane system is kept as low as possible by the arrangement of the counterbalance at the lower end of the mantle-support immediately over the edge of the pontoon. These 50 two points are very important for floating cranes, because the dimension of the pontoon

is dependent upon the height and the lateral distance of the center of gravity from the rotatory axle.

One form of construction according to this invention is illustrated in the accompanying 55 drawings, in which—

Figures 1 and 2 represent side elevations of our improved crane in a diagrammatical manner.

In the midst of the pontoon *a* a stationary 60 support *b* is mounted. The turning support *c* is considerably higher than the stationary support and surrounds the latter like a bell-mantle. The turning bearing *d* is formed to receive the horizontal and vertical acting 65 pressures and the support-bearing *e* receives horizontal strains by means of pressure-rolls horizontally arranged. The jib *f* is connected to the rotating support *c* in any known manner and is adjusted and moved 70 by means of a windlass *h*. On the lower end of the bell-mantle *c* and projecting laterally therefrom is arranged a casing *g*, forming a receptacle for the counterbalance *g'*.

Preferably the driving mechanism and 75 gearing *h* or a part of the same are put into the casing, as indicated at *h'*; thus avoiding the necessity of having additional loads.

It will be understood that the details of this construction may be varied without departing from this invention. 80

Having thus fully described the nature of our invention, we declare that what we desire to secure by Letters Patent of the United States is—

1. In a floating rotating crane, in combination a movable jib *f*, a turning support *c* being formed as a bell-mantle in its lower part and carrying said jib, a receptacle *g* arranged at the lower end of said bell-mantle, a counterbalance mounted in said receptacle 90 for keeping the center of gravity of the crane system as near as possible over the pontoon, a stationary support carrying said turning support, means for operating the latter and the jib, substantially as described. 95

2. In a floating crane, in combination a movable jib *f*, a turning support *c* being formed as a bell-mantle in its lower part and carrying said jib, a receptacle *g* arranged at 100

the lower end of said bell-mantle, a driving gear mounted in said receptacle for operating the turning support and for keeping the center of gravity of the crane system as near as possible over the pontoon; a stationary support carrying said turning support, a windlass for operating the latter and the jib, substantially as described.

In witness whereof we have hereunto set our hands in the presence of two witnesses. 10

ALFRED BODE.
KARL BÖTTCHER.
